Application May 3, 1939, Serial No. 84,734

Term of patent 3½ years

To all whom it may concern:

Be it known that I, Pauline Fracchia, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

The characteristic feature of my design resides in the combination on the specific princess dress disclosed of the specific panels of lacing extending from the hip line to the square neck opening and terminating in bows at the neck in association with the drop shoulder yoke and the tie belt as shown.

I claim:

The ornamental design for a dress, substantially as shown and described.

PAULINE FRACCHIA.
